(57) **CLAIM**

I claim the ornamental design for a shoulder gun holster, as shown and described.

DESCRIPTION

FIG. 1 is a front view of the shoulder gun holster.

FIG. 2 is a rear view of the claimed design.

FIG. 3 is a left side view of the claimed design.

FIG. 4 is a right side view of the claimed design.

FIG. 5 is a top view of the claimed design.

FIG. 6 is a bottom view of the claimed design; and, FIG. 7 is a perspective view of the claimed design shown in use.

The broken lines showing a torso and a gun in FIG. 7 represent environmental subject matter and form no part of the claimed design.
